UNITED STATES PATENT OFFICE.

ROY W. WONSON, OF STAUNTON, VIRGINIA.

DESIGN FOR A FINGER RING.

Application filed February 3, 1927. Serial No. 20,597. Term of patent 14 years.

To all whom it may concern:

Be it known that I, Roy W. Wonson, a resident of Staunton, county of Augusta, State of Virginia, and a citizen of the United States, have invented a new, original, and ornamental Design for Finger Rings, of which the following is a specification, reference being had to the accompanying drawing, forming a part thereof.

Figure 1 is a perspective view of a finger ring embodying my design;

Figure 2 is a view in elevation of the opposite edge from that shown in Figure 1.

I claim:

The ornamental design for a finger ring as shown.

In testimony whereof I hereunto affix my signature.

ROY W. WONSON.
